UNITED STATES PATENT OFFICE.

ALBERT F. PRESTON, OF BOSTON, MASSACHUSETTS.

MOLD FOR BOOTS AND SHOES.

SPECIFICATION forming part of Letters Patent No. 269,460, dated December 19, 1882.

Application filed October 16, 1882. (No model.)

To all whom it may concern:

Be it known that I, ALBERT F. PRESTON, of Boston, in the county of Suffolk, State of Massachusetts, have invented a certain new and useful Improvement in Molds, of which the following is a description sufficiently full, clear, and exact to enable any person skilled in the art or science to which said invention appertains to make and use the same, reference being had to the accompanying drawings, forming a part of this specification, in which—

Figure 1 is an isometrical perspective view of the bed-die of the mold; Fig. 2, a view of a boot or shoe upper formed in the mold; Fig. 3, a view of an upper imperfectly molded; and Fig. 4, a vertical transverse section of the bed-die, taken on the line *rr*, Fig. 1. Fig. 5 is a perspective view of the base-die with the auxiliary die which forms a part of the face thereof removed. Fig. 6 is a perspective view, showing the male die in position on the female die.

Like letters of reference indicate corresponding parts in the different figures of the drawings.

My invention relates to that class of molds which are employed in molding the uppers of boots and shoes; and it consists in a novel construction and arrangement of the parts, as hereinafter more fully set forth and claimed, by which a more effective device of this character is produced than is now in ordinary use.

The nature and operation of the improvement will be readily understood by all conversant with such matters by the following explanation:

In the drawings, A represents the bed-die of the mold; B, the auxiliary die; A', the top or male die, and C the slide. The base-die A is provided with a concavity, D, into which the corresponding convex face of a male die, A', fits. The contour of said male die corresponds to the contour of that portion of the last with which the upper comes in contact in lasting the shoe. The central portion of the concaved face of the die A is provided with a recess or mortise, D, in which is a vertically-movable auxiliary die, B, the face of which corresponds in its outlines with the concavity D of the base die, A, and forms a part of the face of said die A. This auxiliary die rests on springs *m*, interposed between its lower face

and the bottom of the recess. These springs normally hold the auxiliary die above the concave face of the die A, and permit it to be pressed down flush therewith, when the male die comes down upon the base-die. A section, C, of the die A, corresponding with the shank *d* of the upper E, is dovetailed or fitted to slide horizontally in said die, being provided with a spring *x*, for forcing it inwardly or toward the die B, as shown in Figs. 1 and 4.

In molding the upper by means of my improved die, the blank is laid flat or placed horizontally on the auxiliary die B, with the toe *a* over the part *z*, and the ankle *b* over the part *k* of the die A. An upper or male die corresponding with or fitting the bed-die A, and operated by proper mechanism, is then caused to descend, grasping or clamping the blank between the central portion of its face and the die B, where it is securely held until the upper die descends to its fullest extent, and is raised again out of contact with the blank. After the blank is clamped, as described, between the upper die and die B, the upper die continues to descend, compressing the springs *m* and forcing the die B downward until the upper surface is on a level with the bottom of the cavity D in the die A, thus molding the blank, or causing it to conform with the shape of said cavity in a manner which will be readily obvious without a more explicit description.

In dies of this character for molding or forming the uppers of boots and shoes much difficulty has been experienced on account of the tendency of the upper to wrinkle or pucker at the ankle, as seen at G, Fig. 3, the molding process lengthening the lines or edges *g h i l v* of the blank, and thus crowding the stock into the central or ankle portion of the same, where it becomes set or permanently fixed by the action of the die. This difficulty is entirely obviated by means of the auxiliary die B, between which and the upper die the blank is clamped and immovably held until the edges are molded. There has also been more or less difficulty in molding the shank *d* of the upper properly on dies of this character, the stock crowding into this portion of the blank, thus causing the molded upper to be permanently wrinkled, as seen at H, Fig. 3. This defect I

- obviate by so constructing that part of the bed-die opposite the shank that it will yield or slide horizontally, as seen at C, Figs. 1 and 4, and provide the same with a spring, *x*, for forcing it inwardly toward the die B. By this means, when the male die descends, and the shank *d* of the upper E is grasped between the same and the slide C, the slide will yield or move laterally to a sufficient extent to prevent the blank from being crowded together and permanently wrinkled at the shank, as would be the case were the slide not used, on account of the sharp curvature of the dies at this point. I also use a similar slide, when necessary, whenever there is a sharp curve in the dies—as, for instance, above the heel and over the instep—but deem it unnecessary to show more than one to illustrate the principle of this part of the invention.
- 20 An upper molded as described is devoid of wrinkles, conforms to the shape of the last or foot, and will retain its proper form much longer than when molded in the ordinary manner.
- 25 It will be understood that the upper surface of the die B is concaved, or corresponds with the ankle portion of the last or foot, the central portion of the male die being constructed to fit the same.

It will also be understood that two sets of 30 dies are required for each boot or shoe—one to mold the inside and the other the outside quarter.

As I propose to make a boot or shoe upper molded in the manner described the subject- 35 matter of other Letters Patent, I do not claim the same in this application; but,

Having thus explained my invention, what I herein claim is—

1. In a mold for forming the uppers of boots 40 and shoes, the bed-die A, provided with the auxiliary or yielding die B, mounted in a recess or mortise in the die A, substantially as and for the purpose specified.
2. In a mold for forming the uppers of boots 45 and shoes, the bed-die A, provided with the slide C, substantially as and for the purpose set forth.
3. In a mold for forming the uppers of boots and shoes, the bed-die A, auxiliary die B, 50 mounted in a recess or mortise in the die A, and slide C, combined and arranged to operate substantially as described.

ALBERT F. PRESTON.
